UNITED STATES PATENT OFFICE.

CHESTER A. HAGAN, OF NEW YORK, N. Y.

WINDOW LOCK.

Application filed January 19, 1922. Serial No. 530,355.

To all whom it may concern:

Be it known that I, CHESTER A. HAGAN, residing at New York, county of Bronx, and State of New York, have invented certain new and useful Improvements in a Window Lock, of which the following is a specification.

My invention relates to window locks and more especially to a lock to be applied to windows comprising two or more frames in mounted parallel grooves. With such windows it is desirable that means be provided by which the frames, which are relatively movable to an overlying position, may be held against such movement so as to provide a locked closure for the aperture to prevent unauthorized entry.

The one object of my invention is to provide such a window lock which shall be of an attractive appearance and which shall be effective in preventing the relative movement of the window frames.

The second object of my invention is to provide a window lock which may be installed on a window frame with a minimum of operations, which may be adjusted so as to permit complete freedom of movement of the frames, and which may be brought into operative position so as to prevent unauthorized movement.

Another object of the invention is to provide a secure means for locking a window against unauthorized movement which shall at the same time provide the means by which the window may be slightly opened for ventilation purposes.

Another object of the invention is to provide a lock applicable to prevent the relative movement to over-lying position of a pair of window frames, the lock being of such character that it cannot be picked or manipulated from without the building and offering no means by which it may be pried or otherwise forced out of position.

Other objects and aims of the invention more or less specific than those referred to above, will be in part obvious and in part pointed out in the course of the following description of the elements, combinations, arrangements of parts and applications of principles, constituting the invention; and the scope of protection contemplated will be indicated in the appended claims.

In the drawings in which I show a preferred form of my invention:

Figure 1 is a cross-sectional view, with

parts broken away, of a pair of window frames showing my lock in operative position;

Figure 2 is a cross-sectional view of part 60 of a window frame taken on a line through the lock and showing parts of the bolt broken away;

Figure 3 is a cross-sectional view similar to Figure 2 but showing the bolt in inoperative position, the lock being removed;

Figure 4 is a view in elevation of the bolt;

Figure 5 is a view in perspective of the locking key showing the means by which the bolt may be placed in operative position.

Figure 6 is the elevation of a window showing my window lock in position.

In the drawings in which similar reference characters designate similar parts throughout the several views thereof the reference numeral 1 indicates a window frame in which is mounted a sheet of glass, held in place by fillets or moldings 3 in the usual manner. The window frame as shown in Figure 6 is mounted in the wall of the building so as to slide in suitable grooves in a larger frame mounted in the aperture in the wall. Lying adjacent to frame 1 is frame 4 constructed in the same manner as frame 1 and forming in this case, the lower half of the window. The frames 1 and 4 are so mounted as to be relatively movable to a position overlying each other. It will be seen that when the frames are in the over-lying position the aperture in the building is, in the case of a two part window, but half closed.

With windows such as are here described it is desirable that freedom of movement be maintained so that the windows may be raised or lowered so as to provide for ventilation in the building. It is desirable further that some means should be provided by which the two halves of the window may be locked against relative movement, especially in the night-time in order that intruders may be prevented from entering the building. Window locks are provided for this purpose and the ordinary forms consist of a cammed wedge mounted on one of the bars of the frame and engaging a suitable hooked finger mounted on the corresponding bar of the adjacent frame. When the window is to be locked the wedge is rotated or otherwise moved so as to engage the finger. Such locking means are open to a number

of objections, one of which being that such a lock may be easily picked or otherwise manipulated from without the building so as to permit the window to be opened. A 5 second objection is that the window must be closed before the lock may be operated and this makes it impossible to secure ventilation by means of the window when locked.

10 The locking means which is here described overcomes both of the objections stated and in order to mount the new and improved lock in the window, it is only necessary to bore a hole 5 through one of the side bars 6 15 of the window frames at a point relatively near the cross bar 7 which overlies the adjacent frame. On either face of the upright bar 6 there are then mounted face plates 8 and 9, these plates being provided 20 with apertures registering with the bore through the frame. These plates are secured to the frame in any suitable manner 25 as with screws.

In the plate 8 previous to its attachment 30 to the window frame, there is mounted a bolt 10, held in position in the plate by means of a pin 11 which extends through the bolt and projects from either surface thereof to engage the plate 8. The plate 8 is provided 35 with a suitable lateral flange 12, about the aperture, the flange projecting a short distance into the bore in the frame to guide the bolt in its movement. The marginal edge of the aperture in the plate 8 is also reamed as 40 indicated at 13 to provide a seat.

On one end of the bolt there is provided a 45 smooth knob 14 which makes a close fit with the reamed surface or seat on the plate 8 when the bolt is in operative position as shown in Figure 2. The plate 8 is to be 50 mounted in the frame so that the knob 14 of bolt 10 is on the outer surface of the window. On the inner end of the bolt, there is provided suitable locking means which consists 55 in part, of a diametrical bore 15 through the bolt located a short distance from the end opposite the knob. The end surface of the bolt is also diametrically channelled as designated at 16 so that the end of the bolt may be considered as being diametrically slotted and provided with pin 17 mounted between the 60 walls of the slot. The shape of the bore 15 and channel 16 is such that there may be mounted in the inner end of the bolt a suitable locking means such as a padlock 18, the 65 locking arm of which, 19, may be inserted through the bore 15 so as to engage about the locking pin 17. With the padlock in operative position, the bolt is held against movement against the frame and the padlock is held between and against the walls of the slot so as to project almost at right angles of the frame. With the lock in this position, it 70 will be clear that the second frame 4 when being moved so as to occupy an overlying

position relatively to the frame 2 cannot be moved beyond the lock, inasmuch as the end of the bolt and the lock project into the path of the frame 4.

As the second frame may be moved only 70 till it engages the bolt it will be desirable to mount the lock a slight distance above the cross bar 7 as shown in Figure 6, since with the lock in this position, slight relative movement of the two frames is permitted so 75 as to provide for ventilation. However, when the lock is in operation the frames cannot be moved to a complete overlying position so as to permit unauthorized entrance through the window aperture. 80

When it is desired to unlock the window to permit it to be opened to its fullest extent the key 20 is used to release the lock and it is then removed from the bolt. This permits the bolt 10 to be moved to the position shown in Figure 3 in which the inner end of the bolt lies flush with the inner face plate 9. When the bolt is in this position, it will be clear that the two windows may be moved to any position as freely as though 90 the lock were not mounted on the frame. It is desirable of course, that some means be provided by which the bolt may be readily withdrawn from the bore in the frame and to this end there is formed a shallow notch 95 21 in one of the walls of the slot in the end of the bolt. On the end of the key there is also provided a small lateral lug 22 which may be inserted in the notch so as to draw the bolt from the bore to such a position that the 100 padlock may be attached.

It will be seen that my invention provides a safe locking means for window frames which permits the window to be locked against entry while at the same time permitting a slight relative movement of the frames, for ventilation purposes. It will be noted further that the lock may be mounted at any point in the side bar of the window frame, preferably at a short distance from the cross bar, the distance at which the lock is mounted from the cross bar determining the extent to which the frames are capable of relative movement. Ordinarily four and five inches of travel will be sufficient for 105 ventilating purposes. 110

With the locks hitherto in use it has been comparatively simple to insert a slender instrument between the frames so as to move the parts of the lock so that the window may be opened. With the new lock hitherto in use it has been comparatively simple to insert a slender instrument between the frames so as to move the parts of the lock so that the window may be opened. 120

With the new lock herein described it is impossible for any unauthorized person to unlock the window, especially from the outside. Furthermore all exposed parts are provided with smooth rounded surfaces and 125 130

there is no possibility of jimmying the lock inasmuch as any jimmy or prying instrument would only slide off the surface of the knob, the knob seating smoothly in the 5 reamed surface in the face plate.

The bolt and face plates of the improved window lock are preferably made of brass or other metal, such as is commonly used for builders' hardware so as to give the parts 10 an attractive appearance. The lock may be installed on windows prior to their mounting in the window aperture or it may be installed on a window already in use. It is also to be noted that all the parts of the 15 lock are mounted on a single frame of the window so that it is not necessary to provide for careful adjustment such as is necessary in two part locks in which one part is mounted on each frame. Any suitable locking 20 means may be provided for the bolt but I find that a padlock engaging a pin in the slot in the inner end of the bolt is a simple and effective arrangement. While the lock has been shown in use on a window in 25 which two frames are used, it will be clear that it is capable of application to windows having a plurality of frames, though in such cases a number of locks must be used depending of course on the number of frames 30 it is desired to lock against relative movement.

As many changes could be made in this construction without departing from the scope of the following claims, it is intended 35 that all matter contained in the above description or shown in the accompanying drawing shall be interpreted as illustrative only and not in a limiting sense.

Having thus described my invention what 40 I claim as new and desire to secure by Letters Patent is:

1. In a device of the class described, the combination with a pair of window frames, of a bolt movably mounted in one of said 45 frames, and means mounted in said bolt to hold it against movement, said means being also adapted to extend into the path of the second frame to prevent its movement to a position overlying the first frame.

50 2. In a device of the class described, the combination with a pair of window frames, of a bolt movably mounted in an aperture in one of said frames, a pair of plates encircling said aperture on opposed surfaces 55 of said frame, and means mounted in said bolt to lock it in position, said means projecting beyond one of said plates so as to be engaged by said second frame to prevent relative movement of said frames to overlying 60 position.

3. In a device of the class described, in combination with a pair of window frames, a pair of plates mounted on opposite faces of one of said frames and circumjacent an 65 aperture therethrough, a bolt mounted in

one of said plates and movable to operative position to project beyond the other plate, and detachable locking means to hold said bolt in operative position, said locking means being also adapted to prevent relative movement of said frames to overlying 70 position.

4. In a device of the class described, the combination with a pair of window frames, of a pair of apertured plates mounted on inner and outer faces of one of said frames in registry with an aperture therethrough, a bolt movably mounted in one of said plates, means to move said bolt into inoperative position, means to lock said bolt with one end 75 projecting beyond said inner plate, the projecting end of said bolt and said locking means lying in the path of the second frame when moving to over-lying position.

5. In a device of the class described, in combination with a pair of window frames, a pair of apertured plates mounted on inner and outer faces of one of said frames, a bolt mounted in one of said plates and movable to project beyond said other plate, and detachable locking means to lock said bolt in projecting position, said locking means and bolt both lying, while in operative position, in the path of said second frame when moved 90 to overlie said first frame.

6. In a device of the class described, in combination with a pair of window frames, one of said frames being provided with an aperture therethrough a pair of plates circumjacent of said aperture mounted on opposed faces of said frame, a bolt mounted in one of said plates and extending through said frame, said bolt being movable so as to project beyond the other plate when in operative position, and locking means adapted 100 to be mounted in said bolt to lock it in operative position, said bolt and said locking means projecting beyond the face of said plate in the path of movement of the second frame to a position overlying the said first frame.

7. An article of the class described, comprising a pair of apertured plates adapted to be secured to window frame, a bolt movably mounted in one of said plates, and extending through the frame and the other plate, a knob on one end of the bolt and means on the other end of said bolt whereby said knob may be held in contact with one of said plates, said locking means extending outwardly beyond the surface of said second plate.

8. An article of the class described, comprising a pair of apertured plates adapted to be secured to a window frame, a bolt movably mounted in one of said plates, and extending through the frame and the other plate, a knob on one end of the bolt, a seat for said knob formed in the plate about the marginal edge of the aperture, a lock on the 125 130

other end of said bolt to lock said bolt in position with the knob on its seat, the end of said bolt and said lock when in operative position extending outwardly beyond the 5 surface of the frame.

9. An article of the class described comprising, in combination, a bolt movably mounted in an aperture formed through one of a pair of window frames and having an 10 enlarged portion thereon adapted to prevent the removal of said bolt from said aperture in one direction, and means adapted to be mounted in the other end of said bolt to

lock said bolt in position with said end extending beyond the surface of said frame, 15 said locking means being also adapted to lie in the path of said second frame, to be engaged by said second frame when the latter is moved toward a position overlying said first-named frame. 20

In testimony whereof I affix my signature in the presence of two witnesses.

CHESTER A. HAGAN.
